METHOD OF TREATING HYDROCARBON
OILSHarold V. Atwell, White Plains, N. Y., assignor to
Gasoline Products Company, Inc., Newark,
N. J., a corporation of Delaware

Application March 21, 1933, Serial No. 661,898

4 Claims. (Cl. 196—51)

This invention relates to the production of lighter products from relatively heavy hydrocarbon oil, and pertains more particularly to the production of gasoline suitable for use as a motor fuel from heavy hydrocarbon oil such as crude petroleum, reduced crude or the like.

It is an object of my invention to provide a process whereby fresh charging stock may be separated into a relatively light clean cracking stock and a relatively heavy residue of coke forming tendencies, these two stocks being thereafter separately heated, subsequently commingled for digestion and thereafter separated into vapors and liquid residue which are separately soaked with the result that additional conversion of lighter products is attained without detrimental deposition of coke or carbonaceous material.

In accordance with my invention fresh charging stock, which may be crude petroleum, reduced crude, or other comparable oil stock is separated into a relatively light clean distillate cracking stock and a relatively heavy dirty stock of coke forming tendencies. These two stocks are heated, each one preferably being heated to the maximum temperature possible without deleterious coke formation, the former because of its cleaner cracking characteristics being adapted to a higher cracking temperature than the heavy stock. The light stock may for example be heated to from 925 to 975° F., preferably about 950° F., under a pressure in the range of a few atmospheres to 450 pounds per square inch, preferably about 200 pounds per square inch. The heavy oil because of its coke forming tendencies can be cracked only to a lesser degree. A suitable temperature range for this stock would be from 800 to 850° F., preferably about 825° F., while the pressure might be substantially the same as that exerted on the light oil during the cracking thereof, but these figures would vary somewhat dependent upon the exact character of the oil being treated. The products of conversion resulting from the heating of the light and heavy oils are then commingled with a resulting equalization of the temperature thereof and the commingled products may then be subjected to soaking in a common zone subsequent to which the soaked or digested products are separated into vapors and tar. The two latter products are then further individually soaked with attendant additional conversion and the resulting digested vapors, including those formed from the tar, are introduced into a fractionating zone for separation into a desired gasoline distillate, a cycle stock, and a residue.

These two latter products are of a character

adapted for recycling through the system. Since the vapors and tar are soaked or digested separately their temperature may be individually regulated to produce desired results. Separation of the fresh charge into the constituents mentioned hereinbefore is preferably effected by introducing the charge directly into the fractionating zone.

The above mentioned and further objects and advantages of my invention and the manner of attaining them will be made clear in the following description taken in conjunction with the accompanying drawing.

The drawing indicates in schematic form an oil treating system embodying my invention.

Referring more particularly to the drawing, reference numeral 1 indicates a fractionator, 2 a light oil heater, and 3 a heavy oil heater. Fresh charge, which may for example, be crude petroleum such as 35° A. P. I. mid-continent crude oil, is introduced into fractionator 1 through charging line 4, by action of pump 5. In the fractionator the fresh charge comes into contact with hot vapors and is thereby to a certain extent separated into a light clean distillate stock which is collected on trap out tray 6 and unvaporized residue which collects in the base of the fractionator. The clean distillate fraction collected on the trap out tray is removed through pipe 7 and forced by action of pump 8 through the coils of the light oil heater or furnace 2 in which the oil is heated to a moderately high cracking temperature sufficient for example to produce from 15 to 20% of end point gasoline per pass, preferably about 15%. This temperature may be, for example from 925 to 975° F., preferably about 950° F. The pressure may vary considerably but is preferably about 200 pounds per square inch. Additional light oil from an external source may be introduced into line 7 through pipe 41 to effect a balance of conditions or to take care of surplus stock available elsewhere. The heavy relatively dirty residue collected in the base of fractionator 1 is removed through line 9 and forced by action of pump 10 through the heavy oil heater or furnace 3 in which it is heated to a moderate cracking temperature sufficient, for example, to produce from 8 to 10% of gasoline per pass. This temperature may be, for example, from 800 to 850° F., preferably about 825° F. The pressure may be the same as that existing in the light oil heater, e. g. 200 pounds per square inch, or may be different therefrom in certain instances. Additional heavy oil may be supplied from an external source through pipe 42, whenever desired to effect a balance of con-

ditions or to take care of surplus stock available elsewhere.

The cracked light oil and cracked heavy oil are removed from the heaters 2 and 3, through lines 11 and 12 respectively, under control of adjustable valves 13 and 14. The two streams join and pass through pipe 15, having valve 16, into soaking coil 17, which is preferably fired sufficiently to maintain a substantially constant temperature without imparting sufficient heat to cause deleterious coke formation, but which may be unheated if desired. The mixed oil undergoes further digestion with the accompanying formation of a small percentage of lighter products in the coil and with an accompanying equalization of the temperature of the light and heavy oils. The composite digested stock is carried from the soaking coil 17 into the separating chamber 18 through pipe 19 having control valve 20. In the separating chamber the pressure is preferably substantially the same as that existing in the heaters, allowance being made for the necessary drop in pressure through the soaking coil and connections. This pressure may be for example 175 pounds per square inch. Vapors separate from tar or liquid residue in this separating chamber, the former passing off through vapor line 21 into the vapor phase soaking drum 22, which is maintained under substantially the same pressure as that of the separating chamber and at only a slightly lower temperature, the vapors therein being subjected to further soaking or digestion with accompanying conversion into lighter products. The soaked vapors pass from the soaking drum 22 through vapor line 23 and reducing valve 24 into the fractionator 1, the latter being maintained at a lower pressure, e. g. 50 pounds per square inch. With this method of operation by-pass valves 25, 26, and 27, are closed. Reference numeral 43 indicates a valved draw-off line through which any liquids collecting in the soaking drum 22 may be removed.

Unvaporized residue or tar is withdrawn from the bottom of the separating drum 18 and is introduced into the tar soaker 28 through line 29 having reducing valve 30. The pressure in the tar soaker is preferably somewhat lower than that of the separating drum 18; this pressure may be, for example, 50 to 150 pounds per square inch. In this soaker the tar undergoes additional soaking or digestion but at lower temperature than prevailing in the vapor phase of soaking drum 22, with accompanying conversion of the products into somewhat lighter fractions. The lighter products, as fast as formed, pass off through the vapor line 31 into the fractionator 1, the pressure being reduced, if necessary, by means of valve 31. The temperature in the tar soaker depends somewhat upon the temperature maintained in the preceding apparatus but is suitably in the neighborhood of 800° F. Reference numeral 44 indicates a draw-off line through which unvaporized liquids may be removed from the vessel 28.

In the fractionator the various introduced vapors contact with the fresh charge, aiding in the vaporization thereof, with the result that a portion of the fresh charge is vaporized and deposited on trap out tray 6 as hereinbefore explained. At the same time a heavy unvaporizable residue is collected in the base of the fractionator and a desired gasoline distillate is removed from the top of the evaporator through vapor line 32 and condenser 33 for collection in receiving drum 34. A portion of this condensed material may be pumped back in the usual man-

ner through line 35 into the top of the fractionator as a refluxing medium.

The temperatures attained by the light and heavy oils in passing through their respective heaters are selected so that a maximum amount of conversion is attained without undesirable coking of the coils, the light oil being subjected to the higher temperature on account of its cleaner characteristics. When the two stocks are combined in the soaking coil 17 the heavier relatively dirty oil is raised in temperature by contact with the more highly heated clean oil and added conversion of the heavy oil results during the time interval taken in passing through the soaking coil. The increased temperature causes more conversion of the heavy oil but any carbon formed is not particularly disadvantageous since the conversion is carried out in a confined stream wherein the velocity of the oil is sufficiently high to prevent any undesirable deposition of coke. Subsequent to this digestion, because of the separation of vapors from liquids taking place in the separating drum 18, the resulting vapors and liquids may be separately soaked further with additional conversion, while not in contact with one another.

Another method of operating is to close the valves 16, 30, and 36, and open valves 25, 27, and 37. The fresh charging stock then enters the system in the same manner as described hereinbefore and light condensate from trap out tray 6 is also treated as already described, as well as the heavy residue from the base of the fractionator. A combination of heated products, which may be treated under the same pressure conditions as already mentioned, are then passed directly through bypass line 38 into the separating chamber 18 which is then preferably maintained under a lower pressure than that of the heating coils, e. g. 50 pounds per square inch, with resulting separation of the cracked products into relatively light vapors and unvaporizable tar or residue. Not all of the light cracked products are mixed with the heavy cracked products however, only sufficient passing through line 11 to maintain the desired temperature of the products in the separating drum 18. This temperature may be for example, 850 to 900° F., but is preferably 875° F. This drum may be operated either in such manner as to form a liquid residue or coke by maintaining a suitably high temperature. When residue is removed the flow thereof from the drum may be regulated by manipulation of valve 37.

The remainder of the light cracked products pass directly through line 39 into the vapor phase soaking drum 22, which is preferably maintained under about the same pressure and temperature conditions as existing at the outlet of the light oil heater 2, e. g. 200 pounds per square inch, and 925° F. temperature. The vapors undergo further soaking or conversion in the soaking drum 22 and thereafter pass through the line 23 and reducing valve 24 into the fractionator in the same manner as described hereinbefore. The vapors generated in the separating drum 18 and consisting primarily of cycle stock, pass off through the line 21 and bypass line 40 into the fractionator 1, which, as already mentioned, may be held under a pressure of about 50 pounds per square inch.

In either method of operation the soaking coil 17 might be used to a certain extent if desirable by partially closing both of valves 16 and 25, the flow then being split between the soaking coil

- and bypass pipe 38 in any desired ratio. The light oil and heavy oil heaters 2 and 3 and soaking coil 17 have been indicated as separate and distinct units but this is not necessarily so since 5 all of the various coils might be combined in a single furnace, proper consideration being given to the arrangement of the coils in such manner as to produce the desired temperatures. The soaking coil might be maintained at a proper temperature by convection heat derived from flue gases in those cases where it is desired to prevent a loss in temperature by the oil traveling through the coil.

10 While I have described a particular embodiment of my invention for the purposes of illustration it should be understood that various modifications and adaptations may be made within the spirit of the invention as set forth in the appended claims.

15 I claim:

1. The method of treating hydrocarbon oil which comprises thermally separating charging oil having light and heavy constituents into a light clean fraction and a residue, separately heating both said clean fraction and said residue to produce as large an amount of conversion of each to lighter products as possible without deleterious deposition of coke, combining the two separately heated oil bodies to produce an intermediate change of heat therebetween and also a soaking effect, passing the combined products into a vapor separating zone wherein light vapors are separated from heavier residue, separately soaking said vapors and said residue in individual soaking zones, removing vapors from said soaking zones and combining them in a common frac-

tionating zone and segregating a desired gasoline distillate therefrom, and withdrawing the unvaporized liquids from each of said soaking zones and diverting said liquids from the process.

5 2. The process of treating hydrocarbon oil which comprises introducing crude oil into a fractionating zone in contact with hot vapors whereby a clean reflux condensate and a residue are formed, separately heating said condensate and said residue to cracking temperatures, the former being heated to the higher temperature, combining the separately heated products in a common soaking zone wherein their temperatures are equalized and added conversion to lighter products is accomplished, passing the soaked products into a separating zone wherein separation of vapors from liquids takes place, separately removing said vapors and said liquids to individual soaking zones wherein further digestion thereof takes place and passing digested vaporous products from both of said zones into the said fractionating zone wherein fractional condensation takes place, removing gasoline vapors of desired boiling characteristics from said fractionating zone, and separately removing unvaporized products from said individual soaking zones and diverting the removed liquids from the process.

10 3. A process in accordance with claim 2 wherein said clean condensate is heated to a temperature of about 950° F. and said residue is heated to a temperature of about 850° F.

15 4. A process in accordance with claim 2 wherein heat is added to said common soaking zone in sufficient quantities to maintain substantially constant soaking temperature.
